UNITED STATES PATENT OFFICE.

ANDREW S. REID AND ROBERT REID, OF BEVERLY, MASSACHUSETTS, ASSIGNEES, BY MESNE ASSIGNMENTS, TO ADJUSTABLE FRAME COMPANY, OF MARBLEHEAD, MASSACHUSETTS, A COPARTNERSHIP COMPOSED OF WILLIAM A. WALKER, OF MARBLEHEAD, MASSACHUSETTS, AND MARY REID AND ELIZABETH H. REID, BOTH OF BEVERLY, MASSACHUSETTS.

ADJUSTABLE FRAME.

1,091,245.

Specification of Letters Patent. Patented Mar. 24, 1914.

Application filed February 25, 1913. Serial No. 750,535.

To all whom it may concern:

Be it known that we, ANDREW S. REID and ROBERT REID, citizens of the United States, and residents of Beverly, in the county of 5 Essex and State of Massachusetts, have invented certain new and useful Improvements in Adjustable Frames, of which the following is a specification.

This invention relates to rectangular ornamental frames for holding pictures, which term is intended to include mounted photographs, placards, and other like articles which are usually displayed in frames.

The invention has for its object to provide 15 a simple construction whereby a frame composed of four angular members is provided, the frame being adapted to support the margin of a picture and to detachably secure the same, and being also adjustable to fit pictures of different sizes.

The invention consists in the improvements which we will now proceed to describe and claim.

Of the accompanying drawings:—Figure 25 1 represents a front view of an adjustable frame embodying our invention, the frame being enlarged from its minimum size. Fig. 2 represents a section on line 2—2 of Fig. 1. Fig. 3 represents a perspective view of one 30 of the members of the frame. Fig. 4 represents a section on line 4—4 of Fig. 1.

The same reference characters indicate the same parts in all the figures.

In the drawings, *a*, *b*, *c* and *d* represent 35 four angular frame members each of the general form represented by Fig. 3, and comprising a flat inner portion 2 constituting a part of a picture seat, and an embossed outer portion 3 forming a raised hollow rib 40 or bead at the outer edge of the portion 2. The rib is preferably enlarged to form an ornamental corner portion 4, although said enlargement may be omitted, as shown by Figs. 5 and 6. Each member is made of 45 relatively thin sheet material, preferably metal. When the members are assembled as represented by Fig. 1, they form a rectangular frame, a portion of each member overlapping a portion of the next member, and 50 the overlapping portions being slidable relatively to each other to contract and enlarge the frame. The seat portions and embossed

portions of each member fit closely together as indicated by Figs. 2 and 4. The embossed portions 3 are nested together and prevent 55 relative edgewise displacement of the sections, means being provided whereby separation of the sections from each other by side- 60 wise movement is prevented, said means being preferably provided by forming integral tabs 5 on the inner edges of the portions 2, each tab being bent across the edge of another portion 2 as shown by Fig. 2. The flat portions 2 collectively constitute a rectangular adjustable picture seat for the back of a 65 picture 6, and the embossed portions 3 collectively constitute a continuous rectangular adjustable bead surrounding the seat and the margin of a picture thereon. The seat is covered and concealed by the picture. 70

A picture 6 represented by dotted lines in Fig. 2 is laid upon the seat portions 2 and is surrounded by the embossed portions 3. To confine the picture upon the said seat portions we provide flexible ears 7, the side and 75 end portions of which are detached from the portions 2 by U-shaped slits cut therein, said ears being adapted to lie flush with the portions 2 so that they may slide under the portions 2 of other members, and being also 80 adapted to be bent outwardly and caused to overlap the picture 6, as shown by Fig. 2.

The described frame may be suspended on a wall or it may be adapted to stand on a flat surface like an easel. To permit the picture 85 to stand as last described, we provide a brace comprising a clip 8 adapted to detachably engage two overlapping seat portions 2, and an arm 9 projecting rearwardly from the clip and adapted to bear on a table or desk 90 top 10, and support the frame in an inclined position as shown by Fig. 4. The brace is preferably made of thin sheet metal so that the outer arm of the clip is adapted to lie behind the picture 6, the arm 9 being 95 preferably longitudinally embossed to give it sufficient stiffness.

The outer edges of the outer embossed portion 3 may have tabs 12 which are bent inwardly under the edges of the inner embossed portion as shown by Figs. 2 and 4. 100

What we claim and desire to secure by Letters Patent is:—

An adjustable frame composed of four

angular members of thin sheet material each having a flat inner portion, and an embossed outer portion, the members being slidably connected and collectively forming 5 a rectangular adjustable seat for the back of a picture and a continuous rectangular adjustable bead projecting outwardly from and surrounding said seat and the margin of a picture thereon, said members being 10 provided with means for engaging the front

of a picture and holding its back against the seat, and with means for confining the members in slidable contact with each other.

In testimony whereof we have affixed our signatures in presence of two witnesses.

ANDREW S. REID.
ROBERT REID.
